UNITED STATES PATENT OFFICE.

LESLIE W. CLAYBURN, OF MILWAUKEE, WISCONSIN.

SHAVING MACHINE.

Application filed September 23, 1926. Serial No. 137,365.

My invention relates to shaving machines for shaving printing plates, including so-called electroplates, etchings, stereotypes, and the like.

5 It is the object of my invention to provide a novel arrangement and structure of rotary cutter-head, shaving means and pressure means, so arranged and constructed that the rotary cutter-head reduces the printing plate 10 to proximate thickness, followed by the action of the shaving means, to produce a completely shaved printing plate in novel manner, at a single passage thereof past said cutting devices; and, further, to provide novel hold- 15 down means occupying narrow space adjacent to the rotary cutter-head and arranged to press independently upon the various portions across the printing plate, with pressures to cause all portions of the printing surface 20 of the printing plate to be brought into the same surface, and to cause uneven portions thereof to be evened with relation to each other, so that the back of the printing plate will be acted on by the cutting agencies in 25 manner to produce a printing plate of even thickness throughout the areas of its printing surfaces, and to produce a printing plate in which the necessity for make-ready, for printing with an even pressure is reduced to 30 the minimum.

It is the object of my invention, further, to provide novel means whereby to adjust the distances between the rotary cutter-head, the shaving means and the pressure means, and the support for the printing plate; further, to provide novel means whereby to adjust said respective means with relation to each other; further, to provide novel means whereby to provide a compact arrangement of rotary cutter-head, shaving means, and hold-down means at the respective sides of the rotary cutter-head and between the rotary cutter-head and the shaving means; and, further, to provide a novel arrangement of 45 means for causing cutting movement and travel between the cutting agencies and the printing plate.

The invention will be further readily understood from the following description and 50 claims, and from the drawings, in which latter:

Fig. 1 is a side elevation of my improved device.

Fig. 2 is a front end elevation of the same.

Fig. 3 is a rear end elevation of the same. 55
Fig. 4 is a plan view of my improved de-
vice.

Fig. 5 is a cross-section of the same, taken on the line 5—5 of Fig. 1, partly broken away.

Fig. 6 is a vertical longitudinal section, 60 taken on the line 6—6 of Fig. 4.

Fig. 7 is an enlarged sectional detail of the same, showing the cutting devices and the hold-down means.

Fig. 8 is a front elevation of a detail of the 65 hold-down means, partly in section on the line 8—8 of Fig. 1; and,

Fig. 9 is a horizontal section of a detail of the same, taken on the line 9—9 of Fig. 8.

In a companion application for patent on 70 improvements in shaving machines, filed by me September 21, 1926, as Serial No. 136,841, copending herewith, I have shown, described and claimed the travel between the cutting agencies and the support for the printing 75 plate as accomplished by movement of said support and have broadly claimed the means for obtaining such relative travel, and also claimed the species therein shown and described. In the present application I have 80 shown, described and claimed means whereby the travel between the cutting agencies and the support for the printing plate is accomplished by movement of the cutting agencies.

In my aforesaid copending application I 85 have furthermore shown and described the adjustment for adjusting the space between the cutting devices and the support for the printing plate, in order to produce printing plates of different thicknesses, as accom- 90 plished by adjustment of said cutting devices and of the hold-down means, and have broadly claimed the means for adjustment of distance between the cutting devices and hold-down means on the one part and the support 95 for the printing plate on the other part, and also claimed the species therein shown and described.

The adjustment between the cutting devices and hold-down means on the one part, and the support for the printing plate on the other part, is shown, described and claimed in the present application as accomplished by means which obtain adjustment of said support.

In the present exemplification the frame 100 of the machine is exemplified at 11. A bed 12 has thereon a supporting face 13 for the

printing plate, exemplified at 14, and forms a table for the printing plate. The printing surface 15 of the printing plate is presented toward the supporting face of the table. The 5 supporting face of the table is represented as a plane surface.

The bed 12 is shown as a slide, guided up and down in guideways 18 between the bed and the main frame. A wedge-slide 19 is 10 arranged to be moved lengthwise of the main frame, and has guideways 20 between it and the bed, and guideways 21 between it and the main frame. These guideways converge toward one end of the wedge-slide, whereby 15 movement of the wedge-slide in one direction causes raising of the bed and movement of the wedge-slide in the opposite direction causes decent of the bed.

The endwise movement of the slide is 20 shown accomplished by means of a screw-rod 25 threaded in a threaded lug 26 on the wedge-slide, and journaled in a bearing 27 in the end of the main frame. A hand-wheel 28 is fixed to the screw-rod. The screw-rod 25 is held endwise in the bearing 27 by said hand-wheel at one end of said bearing and a collar 29 fixed to said screw-rod at the other end of said bearing. The periphery of the hand-wheel may be provided with a graduated scale 30, with which a finger 31 on the main frame coacts, for indicating the number of turns and part-turns of the hand-wheel for determining the adjustment to height of the bed.

35 A carriage 35 is arranged to travel back and forth lengthwise of the main frame, being guided by guideways 36 between the frame and the carriage. The carriage has on it a rotary cutter-head 37, a shaving means 38, and hold-downs 39, 40, the latter being shown at the respective sides of the rotary cutter-head, and the hold-down 40 being shown between the rotary cutter-head and the shaving means.

45 The travel of the carriage is shown accomplished by providing the carriage with a threaded nut 41 at each side thereof, in which screw-rods 42 are threaded. Each of the screw-rods is journaled and held endwise in 50 a bearing 43 on the main frame, and has a spiral gear 44 fixed thereto.

A cross-shaft 45 is journaled in bearings 46 in the main frame, and has spiral gears 47 fixed thereto, which respectively mesh with 55 the spiral gears 44. Suitable means are provided for rotating the cross-shaft, shown accomplished by means of an electric motor 48, suitably secured to the main frame. The rotor of the electric motor has a pulley 49 fixed thereto, a so-called silent chain 50 being received about said pulley and a pulley 51 secured to the cross-shaft 45. Suitable knock-out means may be provided for preventing over-travel of the carriage.

65 The rotary cutter-head 37 is provided with

axles 55, journaled in bearings 56 upon the carriage. These bearings may be adjusted, as by forming the same as bearing-blocks, the bearing-block at each end of the carriage being slidable in a guideway 57 in the carriage. 70

Hollow adjusting bolts 58 are threaded in threaded lugs 59 on the blocks and bear against the carriage. Clamp-bolts 60 are received through the bores of the bolts 58 and are threaded into the carriage. Jam-nuts 61 about the bolts 58 clamp said bolts and the bearing-block together. 75

The cutter-head is suitably rotated, as by means of a belt 66 received over a pulley 67 fixed to one of the axles 55. Directing pulleys 68, 69, are mounted on axles 70, 71, fixed to the carriage. A pulley 72 is fixed to the cross-shaft 45 at one end of the main frame. A pulley 73 rotates about an axle 74 fixed to the outer end of the main frame. The belt for rotating the rotary cutter-head is received about the pulley 72 for being driven thereby. It also passes loopwise about the pulley 73. 80

The upper stretch of the loop of the belt is received about the under and proximate faces of the pulleys 68, 69, as an upwardly extending loop 75 and about the pulley 67 on the rotary cutter-head for rotating the latter. As 85 the carriage travels back and forth lengthwise of the main frame, the upwardly extending loop 75 moves progressively along the upper stretch of the loop between the pulleys 72, 73, at the respective ends of the machine, for maintaining driving relation between said belt and the pulley 67 on the rotary cutter-head. 90

The rotary cutter-head is shown as having cutter-blades 81 integral therewith, although the cutter-blades may be releasable. The cutter-blades are shown of spiral form. The cutter-blades respectively have a cutting edge 82, a clearance face 83 in rear thereof, and a guiding face 84 at the front of the cutter-blade. This guiding face may be ground for sharpening the cutter-blade. The guiding face guides or directs the chips and shavings made by the rotary cutter-head so as to clear the printing plate and the cutter-head. 105

110 Shaving means coact with the rotary cutter and are shown as a shaving knife 85, which may be termed a fixed knife, in contradistinction to the rotary cutter-head, and is fixed in position relative to the axis of rotation of the rotary cutter head. The shaving knife is shown as an integral knife extending cross-wise of the machine, but it will be readily understood that the same may be made in sections. 115

The shaving knife includes a cutting edge 86, in rear of which there is a bearing face 87, arranged to bear upon the rear face of the printing plate. The bearing face is a narrow flat face which holds all portions of the print- 120

ing plate adjacent to the cutting edge downward to prevent gouging of the printing plate and smooths the rear surface of the printing plate and polishes the same. There is a receding face 88 in rear of the bearing face, which receding face recedes away from the plane of the printing plate for forming a clearance space 89 between the printing plate and the body of the shaving knife.

10 The front end of the shaving knife includes a directing face 90, which aids in directing the direction in which the shavings and chips from the back of the printing plate by the cutting edge 82, shall curl, for ready release 15 and discharge of said shavings and chips. This directing face is so shaped as to permit quite close approach between the shaving edge of the shaving means and the point of coaction between the adjacent pressure means 20 and the printing plate.

The grinding of the shaving knife for sharpening the same preferably takes place upon the bearing face 87.

Means are provided for adjusting the shaving knife, shown as comprising adjustable resistance screws 95, threaded in threaded holes 96 in a cross-piece 97 of the carriage, and clamp bolts 98, received in threaded holes in the fixed knife and extending through 30 slots 99 in said cross-piece. Washers 100 are received between the heads of said bolts and said cross-piece.

Backing bolts 101 may also be provided, the same being threaded in threaded holes 102 35 in the cross-piece 97, and secured in adjusted positions by jam-nuts 103. These backing bolts are used for the purpose of adjusting the distance of the shaving knife with relation to the path of rotation of the cutting 40 edges of the rotary cutter-head.

When adjusting the fixed knife, the clamp bolts 98 are partly relieved, and the adjusting screws 95 adjusted, for causing approach or recession of the cutting edge of the fixed 45 knife with relation to the plane of the support of the printing plate, and the backing bolts 101 adjusted, for adjusting the fixed knife with relation to the rotary cutter-head, whereupon the clamp bolts 98 are clamped 50 for holding the fixed knife in adjusted position.

The rotary cutter-head and the shaving means form cutting agencies for the rear face of the printing plate for reducing the printing plate to the desired thickness. The rotary cutter-head does the rough cutting for proximate thickness of the printing plate and the shaving means perform the precision cutting for finished thickness of the printing 60 plate. The thickness of the shaving produced by the shaving means is determined by the relative adjustment to elevation of the rotary cutter-head and the fixed knife. The thickness of the printing plate is determined 65 by the adjustment of the bed.

Hold-down means are provided for the printing plate for pressing preferably all portions of the printing surface of the printing plate toward the supporting surface, so as preferably to bring all portions of the 70 printing surface into parallelism with the supporting surface, and iron out all unevenness there may be in said printing surface, caused for instance by depressions, exemplified at 104, therein, so as to bring the 75 printing lines in the whole of said printing surface into parallelism with said supporting surface, so that when the cutting agencies have coated with the printing plate, the body of the printing plate will be so cut as to have 80 an even thickness throughout its printing portions.

The hold-down means are exemplified as acting in close proximity to the rotary cutter-head in advance of the rotary cutter-head, 85 and hold-down means are exemplified as acting in close proximity to the rotary cutter-head at the feed-out side of the latter, and in close proximity to the feeding-in side of the 90 shaving means.

The hold-down means are exemplified as rollers 111, journaled on pins 112, fixed in the tines of forks 113. These forks and rollers are preferably arranged close together end to end across the plate supporting surface 95 of the shaving machine. The forks are shown provided with cylindrical bodies 114, movable endwise in bores 115 in a cross-bar 116. Springs 117 are located in said bores, and surround stems 118 extending from said 100 bodies and passing through central holes 119 of plugs 120 threaded in the threaded ends of said bores, the outer ends of said stems being threaded for receiving nuts 121. Turning of said bodies in said bores is prevented 105 by having flat faces 122 between said bodies and the walls of said bores.

Adjustments of the plugs 120 and nuts 121 adjust the tensions of the springs and the limit of outward movements of the pressure 110 rollers toward the supporting surface of the printing plate, whereby the relation of the pressure rollers to the printing surface and the pressure of the pressure rollers upon the printing plate are adjusted. Separate adjustments of the rollers are thus provided.

If it is desired to collectively adjust the rollers, the cross-bar 116 is adjusted so as to cause approach or recession of all of the rollers with relation to the printing plate. 120 This cross-bar is provided with tongues 125 at its respective ends received in grooves 126 in the respective sides of the carriage 35. Adjusting bolts 127 are rotatable and held 125 endwise in bearings 128 of lugs 129 extending from the frame of the carriage. These adjusting bolts are threaded in the cross-bar at the respective ends of the latter. Clamp bolts 130 are threaded in said lugs and are arranged to bear upon the cross-bar at its 130

respective ends for holding the same in adjusted positions.

The hold-down means 39 are similar to the hold-down means 40, with the exception that 5 the parts are reversed with relation to the rotary cutter-head. The forks of said respective hold-down means and the rollers therein are projected under the cylindrical path of rotation of the cutting edges of the 10 cutter-head, into close proximity to the line of cutting action between the cutter-head and the printing plate. The parts of the hold-down 39 are designated by reference numerals similar to those of the respective 15 parts of the hold-down 40, but raised to the series 200.

I do not in this application broadly claim 20 the adjusting relation of the rotary cutter-head and shaving means and hold-down means with relation to each other and to the support for the printing plate, or the means 25 for causing travel between said cutting agencies and the printing plate, having broadly claimed the same in my said copending application for patent Serial No. 136,841, filed September 21, 1926, but do herein claim the species of such adjustments and means for travel herein shown and described.

While I have shown the cutting agencies 30 and hold-down means coacting with a support for a printing plate having right line travel therebetween, it is obvious that said cutting devices and hold-down means may coact with a supporting face formed as the 35 sector of a cylinder, for instance for coacting with curved printing plates.

Having thus fully described my invention, what I claim as new, and desire to secure by Letters Patent, is:

40 1. In a printing plate shaving machine, the combination of a support for the printing plate, a rotary cutter-head and shaving means coacting with said support, sectional hold-down means at each side of said rotary cutter-head and between said rotary cutter-head and said shaving means, said rotary cutter-head, shaving means and sectional hold-down means located in close juxtaposition lengthwise of the machine and all operating on the same portions of the back of 45 the printing plate, and means for causing travel between said support and said rotary cutter-head, shaving means and hold-down means.

55 2. In a printing plate shaving machine, the combination of a support for the printing plate, a rotary cutter-head and shaving means for the printing plate coacting with said support, sectional hold-down means between 60 said rotary cutter-head and said shaving means, said sectional hold-down means extending under the cylinder of the path of rotation of the cutting edges of said rotary cutter-head, said shaving means extending under said hold-down means, and means for

causing travel between said support and said rotary cutter-head, shaving means and hold-down means.

3. In a printing plate shaving machine, the combination of a support for the printing plate, a rotary cutter-head and shaving means for the printing plate coacting with said support, sectional hold-down means between said rotary cutter-head and said shaving means, said sectional hold-down means 70 extending under the cylinder of the path of rotation of the cutting edges of said rotary cutter-head, said shaving means extending under said hold-down means, means permitting independent movement of the respective 75 sections of said sectional hold-down means in paths substantially perpendicular to said support, and means for causing travel between said support and said rotary cutter-head, shaving means and hold-down means. 80

4. In a printing plate shaving machine, the combination of a support for the printing plate, a rotary cutter-head and shaving means for the printing plate coacting with said support, hold-down means at the respective 90 sides of said rotary cutter-head and between said rotary cutter-head and said shaving means, said hold-down means comprising pressure devices presented toward each other at the respective sides of said rotary cutter-head and extending under the cylinder of the path of rotation of the cutting edges of said rotary cutter-head, each of said hold-down means comprising independent hold-down parts arranged side by side lengthwise of 95 said rotary cutter-head; and said shaving means extending under said hold-down means which are located between said rotary cutter-head and said shaving means, and means for causing travel between said support and said rotary cutter-head, shaving means and hold-down means.

5. In a printing plate shaving machine, the combination of a support for the printing plate, a rotary cutter-head and shaving means 100 for the printing plate coacting with said support, sectional hold-down means between said rotary cutter-head and said shaving means, said sectional hold-down means extending under the cylinder of the path of rotation of the cutting edges of said rotary cutter-head and said shaving means extending under said hold-down means, a support for said sectional hold-down means, means permitting independent yielding movement of the sections of 105 said sectional hold-down means on said second-named support in paths substantially perpendicular to said first-named support, means for adjusting said second-named support toward and from said first-named support, and means for causing travel between 110 said support and said rotary cutter-head, shaving means and hold-down means.

6. In a printing plate shaving machine, the combination of a frame, a printing plate sup- 115

- porting table on said frame, means for adjusting said table on said frame, a carriage; a rotary cutter-head, shaving means and resiliently acting sectional hold-down means coacting with said table and mounted on said carriage, a pulley on said carriage for said rotary cutter-head, direction pulleys on said carriage, pulleys at the respective ends of said frame, a driving belt received about said 10 last-named pulleys and comprising a stretch received about the proximate faces of said direction pulleys and about said first-named pulley, and means for causing travel of said carriage on said frame with relation to said 15 table.
7. In a printing plate shaving machine, the combination of a frame, a printing plate supporting table on said frame, a carriage on said frame, a rotary cutter-head journaled on said 20 carriage, shaving means on said carriage at the side of said rotary cutter-head, hold-down means on said carriage at the side of said rotary cutter-head, adjusting means on said carriage for adjusting said rotary cutter- 25 head, said shaving means and said hold-down
- means independently for distance relation with said table, and means for adjusting said table for distance relation with said rotary cutter-head, said shaving means and said hold-down means, and means for causing 30 travel of said carriage.
8. In a printing plate shaving machine, the combination of a support for the printing plate, a rotary cutter-head and shaving means coacting with said support, sectional hold-down means alongside said rotary cutter-head, said sectional hold-down means comprising a bar extending lengthwise of said cutter-head, said bar provided with bores arranged side by side in said bar, spring-pressed plungers in said bores, said plungers provided with printing plate contact means for pressing said printing plate toward said support, and means for causing travel between said support and said rotary cutter-head, 40 shaving means and hold-down means.

In testimony whereof, I have hereunto signed my name.

LESLIE W. CLAYBOURN.
